UNITED STATES PATENT OFFICE

138,757

DESIGN FOR A HOSPITAL LIBRARY CART

Mary W. Standlee, Washington, D. C.

Application December 6, 1943, Serial No. 111,904

Term of patent 14 years

(Cl. D33—14)

To all whom it may concern:

Be it known that I, Mary W. Standlee, a citizen of the United States and a resident of Washington, in the District of Columbia, have invented a new, original, and ornamental Design for a Hospital Library Cart, of which the following is a specification, reference being had to the accompanying drawing, forming part thereof.

Fig. 1 is a perspective view of the hospital library cart, showing my new design; and
Fig. 2 is a side elevational view of same.

I claim:

The ornamental design for a hospital library cart, as shown.

MARY W. STANDLEE.
